R. CUMMING

LOOSE LEAF BINDER

Filed Jan. 15, 1926

Inventor
Robert Cumming
by *Sutherland & Co.*
Attns.

UNITED STATES PATENT OFFICE.

ROBERT CUMMING, OF TORONTO, ONTARIO, CANADA.

LOOSE-LEAF BINDER.

Application filed January 15, 1926. Serial No. 81,490.

My invention relates to improvements in loose leaf binders, and the object of the invention is to devise a simple, cheap, easily and quickly operated binder which will not 5 mar or scratch any polished surface upon which it may be placed, and will exert a constant and even grip upon the loose leaves to hold them tightly in place and which automatically secures itself in the tightened position, and it consists essentially of the arrangement and construction of parts as 10 hereinafter more particularly explained.

Fig. 1 is a perspective view of a loose leaf book with my device applied thereto.

Fig. 2 is a perspective view of the back end of the book.

Fig. 3 is a sectional plan view showing the book back a portion in elevation and 20 the operating mechanism mostly in section.

Fig. 4 is a cross sectional view on line 4—4 Figure 3.

Fig. 5 is a cross sectional view on line 5—5 Figure 4.

Fig. 6 is a fragmentary detail of a portion 25 of one of the loose leaves showing the slot through which the securing member extends.

In the drawings like characters of reference indicate corresponding parts in each 30 figure.

1 and 2 indicate the covers of the book between which are held the loose leaves 3. The leaves 3 are provided with slotted openings 4 which are in vertical alignment one 35 with the other when within the book and through which the securing means is adapted to pass.

5 and 6 are the back members of the book covers hingedly connected at 7 and 8 to the covers 1 and 2.

9 and 10 are link members pivotally connected to the back members 5 and 6 in proximity to each end thereof as indicated at 11 and 12. The free ends of the members 9 and 45 10 have a tongue and jaw connection as indicated at 13 provided with aligned orifices 15 and 16 through which the operating spindle is adapted to pass as clearly indicated in Figure 3. The operating spindle comprises two members 17 and 18. The member 17 is slightly reduced as indicated at 50 19. The member 18 is in the form of

a hollow cylinder which fits onto the reduced portion 19 so as to be turnable thereon.

20 and 21 are knobs formed at the outer ends of the members 17 and 18 and which are operated manually as will hereinafter appear.

23 and 24 are clutch members secured 60 respectively to the members 17 and 18 and provided on their inner face with radial ratchet clutch teeth 25 and 26 which engage one with the other as shown in Figure 2.

When the teeth are in engagement as 65 illustrated and the knobs 20 and 21 are gripped in either hand of the operator the spindle members 17 and 18 may be turned in opposite directions so that the clutch teeth will slip one over the other and re-engage 70 by manual inward pressure at the end of the movement.

27 and 28 are straps of leather or canvas or any other suitable material secured at one end to the member 17 preferably by 75 passing through diametric slots therein and being secured in such slots. The opposite ends of the straps pass respectively to the outside of the back members 5 and 6 and pass through slots 29 and 30 and through vertically aligned slots 4 of the loose leaves 3, the free ends being secured to the inner face of the back members 5 and 6 as indicated at 31 and 32.

33 and 34 are similar strap members secured in a similar manner to the member 18, the free ends also passing over the outer faces of the back members 5 and 6 to pass through the slots 29 and 30 formed in the other end of the book.

It will thus be seen that when the knobs 20 and 21 are turned in the manner above described, or in the directions of the arrows shown in Fig. 2, the straps 28, 33 and 34 are drawn in the direction of the respective arrow so as to be wound upon the spindle members 17 and 18. The straps 27 and 28 are wound on the spindle 17 in a direction opposite to that in which the straps 33 and 34 are wound upon the spindle member 18, and thus the back members 5 and 6 are drawn together.

It will be readily seen that the device adjusts itself to the thickness of the book by

means of the links 9 and 10, the spindle formed by the members 17 and 18 always remaining in central alignment with the book back, the links 9 and 10 spreading outward 5 to correspond to the thickness of the book.

The leaves 3 are provided with slots 4 through which the securing straps 27 and 28, 33 and 34 pass. The back portion of the leaf forming the back wall of the slot is slit 10 as indicated at 3° to permit the insertion of the leaves in the book by passing the strap through such slit into position in the slot.

When it is desired to insert a new leaf in 15 the book or remove one therefrom all it is necessary to do is to turn the spindle members 17 and 18 in the opposite direction to arrow so as to loosen the straps 27 and 28, 33 and 34 from their tightened position and 20 then spread the back members 5 and 6 apart and slip the desired leaf from the strap by permitting the strap to pass through the slits 3°.

When turning the knobs 20 and 21 in opposite directions as above described to wind the straps 27 and 28, 33 and 34 upon the members of the divided spindle so as to pull them taut it will be readily seen that the pull of the straps on one side of the 30 book centre is in opposite direction to that of the straps on the opposite side of the book centre and therefore the pull is equal in both directions tending to turn one member of the spindle in one direction and the other member of the spindle in the opposite direction, the pull of one member balancing the pull of the other member and thereby holding the spindle as a whole stationary so that it will not turn in either direction.

From this description it will be seen that I have devised a very simple, cheaply constructed, easily and quickly operated loose leaf binder which has no sharp corners or parts liable to scratch any polished surface 45 upon which it may be placed, such as a desk, the straps 27 and 28, 33 and 34 contacting with the desk and thereby preventing the metal parts rubbing upon the surface. At the same time I have devised a loose leaf binder which will exert a constant grip upon 50 the leaves to hold them tightly in place so that there is no possibility of their becoming loose in the binder and by which the tension exerted remains even from one side of the binder to the other, and therefore I have devised a loose binder which secures itself automatically after each tightening operation.

What I claim as my invention is:

1. In a loose leaf binder, the combination with the back members, of a spindle divided centrally of its length, links pivotally mounted on each back at one end and through the opposite ends of which the spindle extends 65 to pivotally connect the links together, straps

secured to the spindle members at one end and so connected to the back members as to pull them towards each other by turning of the spindle members in opposite directions, and means for detachably locking the 70 spindle members together at the end of their turning movement.

2. In a loose leaf binder, the combination with the back members having slots therein and loose leaves inserted between the back members having slots in alignment with the aforesaid slots, of straps secured to each back member and extending through the slots of the leaves and through the slots of the opposing back member, bearing members carried by the back members, a spindle divided centrally of its length into two members mounted to turn in opposite directions in such bearing members and provided with turning knobs at its outer ends and to which the straps are connected so that the straps extending from one back member are wound in an opposite direction to the strap extending from the other back member when the spindle members are turned in opposite 80 directions, and means between the members of the spindle for automatically connecting them together at the end of the tightening operation.

3. In a loose leaf binder, the combination with the back members having slots therein and loose leaves inserted between the back members having slots in alignment with the aforesaid slots, of straps secured to each back member and extending through the slots of the leaves and through the slots of the opposing back member, bearing members carried by the back members, a spindle divided centrally of its length into two members mounted to turn in opposite directions in such bearing members and provided with turning knobs at its outer ends and to which the straps are connected so that the straps extending from one back member are wound in an opposite direction to the strap extending from the other back member when the spindle members are turned in opposite 90 directions, and means between the members of the spindle for automatically connecting them together at the end of the tightening operation.

4. In a loose leaf binder, the combination with the back members having slots therein and loose leaves inserted between the back members having slots in alignment with the aforesaid slots, of straps secured to each back member and extending through the slots of the leaves and through the slots of the opposing back member, bearing members carried by the back members, a spindle divided centrally of its length into two members mounted to turn in opposite directions in such bearing members and provided with turning knobs at its outer ends and to 100

- which the straps are connected so that the straps extending from one back member are wound in an opposite direction to the strap extending from the other back member when
- 5 the spindle members are turned in opposite directions, and a clutch member mounted on each spindle member and having oppositely directed ratchet teeth in the opposing face of such clutch members adapted to engage one with the other at the end of the oppositely directed turning movement of the spindle members.

ROBERT CUMMING.
